UNITED STATES PATENT OFFICE

133,575

DESIGN FOR A HEAT PRESERVER

William C. Knepper, Asheville, N. C.

Application April 8, 1942, Serial No. 106,492

Term of patent 14 years

To all whom it may concern:

Be it known that I, William C. Knepper, a citizen of the United States, residing at Asheville, in the county of Buncombe and State of North Carolina, have invented a new, original, and ornamental Design for a Heat Preserver, of which the following is a specification, reference being had to the accompanying drawing, forming part thereof.

Figure 1 is a side view of a heat preserver showing my new design.

Figure 2 is a top plan view.

Figure 3 is a bottom plan view, and

Figure 4 is a sectional view taken substantially on the line 4—4 of Figure 2.

I claim:

The ornamental design for a heat preserver, as shown.

WILLIAM C. KNEPPER.
